CIGARETTE BOX

William S. Groom, Fort Mitchell, Ky., assignor
to William Bots, Fort Mitchell, Ky.

Application March 29, 1946, Serial No. 658,000

7 Claims. (Cl. 312—83)

1

The present invention relates to improvements in novelty cigarette boxes and has for its principal object the construction and cooperation of certain elements of a receptacle to provide for normal storage and protection of cigarettes contained therein and upon manual rotation of said receptacle to automatically transfer a single cigarette from storage to an accessible, dispensing position.

Another object of the invention is to provide a two-part cigarette box which positively dispenses one cigarette by a manually instituted, rotatory movement of the box thereby obviating the use of push buttons, levers, or other similar cigarette dispensing mechanisms.

A further object of the invention is to provide a cigarette box of the above stated character which has a simple and durable structure, has a positive dispensing action, is attractive in appearance, and is inexpensive to manufacture.

With these ends in view this invention consists in the details of construction and combination of elements hereinafter set forth in the specification, illustrated in the accompanying drawings, and specifically designated in the claims.

In the drawing:

Fig. 1 is a perspective view of my cigarette box in an inverted dispensing position.

Fig. 2 is a cross-sectional view taken through the longitudinal center of the box illustrated in Fig. 1.

Fig. 3 is a cross-sectional view taken on line 3—3 of Fig. 2.

Fig. 4 is a cross-sectional view similar to that of Fig. 3 showing my box in normal storage position.

Fig. 5 is a cross-sectional view similar to that of Fig. 3 showing the box approaching its cigarette dispensing position.

Referring to the drawing the numeral 10 indicates an open bottomed box having side walls 11 and 12, end walls 13 and 14 and a top wall 15. As is clearly illustrated in Figs. 1 and 3 the longitudinally extending, elongated side walls 11 and 12 are somewhat thicker than the end walls and to this end each wall may have a supplemental section 16 and 17 secured to its respective inner surface. Preferably each of these sections 16 and 17 has formed therethrough a longitudinally extending slot 18 and 19 respectively. As indicated in Figs. 2—5 each slot has an upper and lower side which is downwardly inclined toward the box center and each slot is slightly longer and wider than the length and width of a cigarette adapted to be contained in and dispensed

2

by the cigarette box. It will be noted that the walls 11 and 12 of the box serve to close the outer sides of the through slots 18 and 19 respectively, and that said slots are disposed adjacent the bottom edges of the box side walls and open inwardly toward the longitudinal center of said box.

Contained wholly within the box 10 is a cigarette receptacle or hopper generally indicated by the reference numeral 20. This receptacle has a loose fit with the inside of the box to permit sliding movement of the receptacle toward and away from the open bottom of the box; said fit, however, is not loose enough to cause undue sidewise or endwise movement of the receptacle within the box during box rotation, as might cause rattling, or vibration between the parts.

The receptacle 20 comprises two opposed end walls 21 and 22 which have extending between them a top wall 23 and foreshortened side walls 24 and 25 preferably constructed from a single sheet of material and secured to said end walls along its transverse edges by means of countersunk nails 26. (Fig. 3.) A V-shaped bottom wall 27 is provided for the receptacle and the lower longitudinal edge of said wall 27 is joined with a central partition 270 which divides the hopper into two cigarette compartments. As most clearly shown in Figs. 2 and 3 the top wall 21 and partition 270 may be constructed from two sections of flat material having lower abutting vertical portions and diverging upper portions, the transverse edges of said portions being held in aligned Y-shaped grooves 28 and 280 formed in the interior surfaces of end walls 21 and 22 respectively. Substantially V-shaped blocks 29 and 30 are respectively secured to the lower interior sides of the receptacle end walls 21 and 22 respectively, the lower transverse edges 31 and 32 respectively of said blocks being inclined toward the center and serving as delivery rails for a cigarette dispensed through either inclined slot 18 or 19, said rails directing said cigarette to semi-circular depressions 33 and 34 formed in the blocks.

Side openings 35 and 36 are formed in the receptacle between the longitudinal edges of the wall 27 and the bottom edges of the foreshortened side walls 24 and 25 respectively, said openings being normally in registry with the slots 18 and 19 respectively when the box is in its normal storage position, indicated in Fig. 4, and out of registry with the slots 18 and 19 respectively when the box is resting on its top wall 15 in dispensing position, as illustrated in Figs. 1—3. The

outer limit of motion of the receptacle 20 within the box 10 is determined by the alignment of the inclined slots in the box with the openings in the receptacle and is fixed by opposed pins 37 and 38 projecting inwardly from end walls 13 and 14 respectively of the box, said pins extending into slots 39 and 40 formed in end walls 21 and 22 of the receptacle 20.

In operation the receptacle 20 is removed from the box 10 by withdrawing pins 37 and 38 and each compartment is charged through its respective opening 35 and 36 with a number of cigarettes 41 and 42 whereupon the parts are reassembled and the whole then inverted to stand upside down on a table or desk. (Figure 4.) During the aforementioned manipulation the hopper falls inside the box, to the position shown in Figure 4 and a cigarette rolls through each of the openings in the sides of the hopper into each of the two slots in the box. Other cigarettes fall behind cigarettes 43 and 44 as indicated in Fig. 4. The box is now in the closed or storage position.

To dispense a cigarette, the outer box is grasped from either end and slowly turned sideways. It may be turned either to the right or left, regardless of which end faces the operator, but it is assumed that it is turned to the right in a clockwise direction.

Before the turn of 180 degrees is half completed cigarette 44 and those which were behind it fall back into the hopper, while cigarette 43 and those behind it remain in the positions shown until the box has been further turned to position shown in Fig. 5. At this point in the turn, the hopper slides to the top 15 of the outer box, and cigarette 43 is by-passed and remains in the slot 19 at one side of the outer box, while the cigarettes behind it, fall back into the hopper of their own weight or are forced back by the descent of the hopper into the bottom of the outer box.

The turning of the box is then continued to complete an arc of 180 degrees from the original closed position as shown in Fig. 4, whereupon the inclination of the wall will initiate movement of the cigarette out of the slot in the box onto the delivery rails 31 and 32 on the bottom of the hopper where the cigarette rolls to the center and comes to rest in the small, semi-circular depressions 33 and 34 and may be picked up by the operator with thumb and forefinger. The box is then inverted against the upside down or closed position (as in Fig. 4) on the desk or table where it is ready for the further dispensing of one cigarette at a time as desired.

As indicated in Fig. 1 my cigarette box may rest normally upon a supporting surface with its open bottom facing upwardly and the box rotated one complete revolution to dispense a cigarette, but, as indicated in Fig. 4, the box preferably assumes a position with its open bottom resting upon said supporting surface. It will be noted that in the latter position, the box effectively precludes the entrance of air and dirt into the cigarette receptacle and the walls may be decorated in any suitable manner to provide an ornamental appearance for my box when not in use.

What is claimed is:

1. In a device of the character described the combination of an open bottomed box having side walls, end walls and a top wall, a horizontal recess formed in one of the side walls adjacent the open bottom thereof, a cigarette receptacle positioned within the box for vertical sliding movement therein, said receptacle having a top wall, side walls, end walls, and a bottom wall, a dis-

charge opening formed in one of the side walls and normally positioned in registry with the recess, and cigarette delivery rails disposed outside the receptacle on the bottom wall thereof and adapted upon rotation of the box to an inverted position to guide a cigarette into dispensed position after retraction of the receptacle into the box so as to clear the recess.

2. In a device of the character described the combination of an open bottomed box having side walls, end walls and a top wall, a horizontal recess formed in one of the side walls adjacent the open bottom thereof, a cigarette receptacle positioned within the box for vertical sliding movement therein, said receptacle having an inverted V-shaped bottom wall, a top wall, end walls and foreshortened side walls, thus forming openings between the foreshortened side walls and the longitudinal edges of the V-shaped bottom wall, said openings being normally in alignment with the recesses, and inclined delivery rails outside of the receptacle on the bottom wall adapted upon rotation of the box to an inverted position to guide a cigarette from the recess to dispensed position thereon after retraction of the receptacle into the box so as to clear the recess.

3. A cigarette box having a top wall, side walls and end walls and an open bottom, the interior faces of said side walls each having formed thereon in a horizontal recess disposed adjacent the open bottom, and a reciprocable cigarette receptacle within the box movable from a dispensing position adjacent the top of the box to a normal storage position adjacent the open bottom upon sidewise rotation of the box, said receptacle having end walls, foreshortened side walls, a top wall and a V-shaped bottom wall having longitudinal edges which form with the top edges of the side walls a pair of opposed cigarette discharge openings normally in alignment with the recess to introduce cigarettes from the receptacle into said recess whereby upon movement of the receptacle to dispensed position a cigarette is guided from a recess onto the bottom wall of the receptacle.

4. In a device of the character described the combination of a box having a horizontal receiving recess formed on the interior face of one of the sidewalls of the box, a cigarette receptacle vertically slidably within the box and having a discharge opening therein normally positioned in registry with the recess whereby a cigarette is initially introduced into the recess from the receptacle said receptacle being of a height such that upon inversion of the box the now top surface of the receptacle is below the recess in the side wall and said now top surface being downwardly inclined from the recess so that the cigarette is dispensed from the recess upon the now top surface of said receptacle.

5. In a device of the character described the combination of an open bottomed box having side walls, end walls and a top wall, a horizontal recess formed in each side wall of the box adjacent its open bottom, a cigarette receptacle positioned within the box for vertical sliding movement therein, said receptacle having an inverted V-shaped bottom wall, a top wall, end walls and foreshortened side walls, a partition between the top edge of the V-shaped wall and the top wall thereon, openings formed between the foreshortened side walls and the longitudinal edges of the V-shaped top wall, said openings being normally in alignment with the recesses, and inclined delivery rails disposed on the outside of the bottom

wall and adapted upon rotation of the box to an inverted position to guide a cigarette from the recess to dispensed position thereon after retraction of the receptacle into the box so as to clear the recesses.

6. In a device of the character described the combination of an open bottomed box having side walls, end walls and a top wall, a horizontal recess formed in each side wall of the box adjacent its open bottom, a cigarette receptacle positioned within the box for vertical sliding movement therein, said receptacle having an inverted V-shaped bottom wall, a top wall, end walls and foreshortened side walls, a partition between the top edge of the V-shaped wall and the top wall therefor, openings formed between the foreshortened side walls and the longitudinal edges of the V-shaped top wall, said openings being normally in alignment with the recesses, and inclined delivery rails disposed on the outside of the receptacle on the bottom wall thereof and adapted upon rotation of the box to an inverted position to guide a cigarette from the recess to dispensed position thereon after retraction of the receptacle into the box so as to clear the recesses.

7. In a device of the character described the combination of a box, an inclined horizontal cigarette receiving recess formed on the interior face of one of the side walls of the box, a cigarette receptacle vertically slidable within the box and having a discharge opening therein normally positioned in registry with the recess whereby a cigarette is initially introduced into the recess from the receptacle, said receptacle being of a height such that upon inversion of the box the now top surface of the receptacle is below the recess in the side wall and said now top surface being downwardly inclined from the recess so that the cigarette is dispensed from the recess upon the now top surface of said receptacle.
